(57) **CLAIM**

The ornamental design for a bogie wheel, as shown and described.

DESCRIPTION

FIG. 1 is a perspective view of a bogie wheel showing our new design;

FIG. 2 is a front elevational view thereof;

FIG. 3 is a rear elevational view thereof; and,

FIG. 4 is a side elevational view thereof, the opposite side elevational and top and bottom plan views being identical to FIG. 4.
